His Attorney

UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

ELECTRIC FURNACE

Original application filed March 31, 1926, Serial No. 98,893. Divided and this application filed July 7, 1927. Serial No. 204,116.

The present invention relates to electric furnaces of the type in which the operations or treatments are carried out in an atmosphere of selected gas in a closed container which is heated by internal resistors or other suitable heating means supplied with electric current from a suitable external source.

More particularly the present invention relates to a furnace of the above-named type for carrying out the process described in my copending application, Serial No. 98,893, filed March 31, 1926, of which this application is a division.

Briefly considered, the above-mentioned process is adapted for uniting by fusion at the joints, the various parts of an assembled structure, particularly a structure having parts which are located in stacked or such other assembled relation to each other that they may be compressed while hot to close the joints between them. By compressing the parts to close the joints, careful preliminary fitting together of the parts is obviated while at the same time the proper capillary spacing between the parts at the joints is obtained, such spacing insuring a flow of fusing metal through the joint and a proper uniting of the parts thereby as is described in my Patent No. 1,659,550.

More specifically the above-mentioned process includes heating such assembled structure or charge with copper or other fusing metal applied adjacent the joints thereof in an electrically-heated furnace in which a controlled atmosphere is maintained. For this purpose a non-oxidizing gas such as hydrogen, for example, is employed and is supplied to the heating chamber of the furnace in regulated amounts. When hydrogen is used as the gas and copper as the fusing metal, the hydrogen not only prevents oxidation of the surfaces to be joined but also acts as a flux which facilitates the flow of the melted copper into and through the joints.

Assuming the proper temperature of the

furnace, the charge is permitted to remain therein until the copper melts and flows chiefly or wholly by capillary action into and through the joints. Now instead of reducing the temperature of the furnace to a point where the copper hardens and completes the joints, or removing the charge while hot and inserting it in a cooler, I immediately subject the hot charge to such mechanical pressure as will force the opposing surfaces of each joint into firm contact. Should there be a high spot at one joint, a yielding of the metal parts will take place at this point because of their heated and somewhat softened condition. On the other hand, should one joint be a trifle low, the pressure applied is sufficient to close the space at what was the low joint and into and through which the copper will then freely flow because of its molten condition and because of the capillary size to which the space has been reduced.

Throughout the process the charge is subjected to the controlled atmosphere and must be quickly pressed before it cools sufficiently for the fusing metal to harden. It must then be as rapidly cooled as possible while being pressed, and for commercial work the process must be practically continuous. This involves the problem of charging and unloading the furnace while in operation as well as the simultaneous heating, pressing and cooling of the successive charges without loss of time or cooling of the charges between the heating and pressing operations.

It is therefore, the object of this invention to provide an improved electric furnace structure which is adapted for meeting the above requirements and which permits the process to be carried out more rapidly and effectively, while being of simple construction and of easy operation. For a consideration of what is believed to be novel, attention is now directed to the accompanying drawing, the description thereof, and the appended claims.

Referring to the drawing, 3 indicates an

electrically-heated furnace having a heating chamber 4 in which the work or charge is located and 5 the electrical heating elements or resistors connected to a suitable source of current in the usual way. The casing of the furnace is made of metal which is heavily lined with heat-resisting material 6. Hydrogen or other selected gas is admitted to the heating chamber preferably at or about the center by the pipe 7 and its controlling valve. 8 indicates a suitable removable partition which divides the heating chamber 4 from a receiving chamber 9 in which the cooling and pressing operation takes place. The partition 8, while serving to prevent the free flow of heat from the heating chamber to the press chamber, is not gas tight so that an atmosphere of selected gas will be maintained in the pressing chamber. If desired, an additional amount of selected gas may be supplied to the press chamber by a pipe and valve such as are used to supply gas to the heating chamber.

In order to move the successive charges from the heating chamber, in which one or more charges may be contained at a given time, to the pressing chamber, an actuator is provided comprising a reciprocating member 10. It may be moved by hand or power, depending upon the weight of the charges. As shown the member has rack teeth which mesh with a pinion 11 which is rotated by a handle or crank 12. As usual sight tubes will be provided at a number of suitable points so that the condition of the charges as well as their respective positions can be determined.

In order to insert the charges in the furnace an elevator 13 of any suitable construction is employed. As shown, it is of the hydraulic type and is controlled by a three way valve 14. Between the lower platen or ram of the elevator and the lower edge of the furnace is a labyrinth packing 15 containing sand or steel shot to prevent the free escape of gas. When the elevator is lowered a charge is deposited on the platen or ram after which it is moved upward to the closed position and the actuator 10 employed to move the charge into its proper position within the heating chamber.

During the period in the cycle of operation that the seal is broken, it is desirable to slightly increase the supply of selected gas to the heating chamber to keep the burning area at or adjacent the mouth of the opening, thereby preventing the entrance of air to the furnace. As an aid in preventing the entry of air into and consequent danger of explosion in the furnace, the openings in the furnace are surrounded by projecting walls indicated at 15^a. These walls provide tubular furnace openings of sufficient length to bring the region of union of gas and air well

away from or below the interior of the furnace, as indicated in the drawing.

After the charge has been heated to a point above the melting point of the fusing metal, the partition 8 is raised and the charge pushed by the actuator 10 on to the lower platen of the hydraulic or other elevator or press 16 which is or may be of the same general construction as the one above described. However, it must be capable of sufficient upward movement after closing the furnace and be strong enough to compress the charge sufficiently to ensure complete jointing or union of the parts thereof.

In some cases it will be desirable to accelerate the cooling by providing artificial cooling means for one or both of the press platens. This may be done by a system of cooling pipes or passages 16^a located in the platens near the face thereof and shown in dotted lines. By more quickly cooling the charge the cycle of operation in some cases can be shortened.

The stationary platen 17 of the elevator is suitably anchored as for example by cross members 18 and vertical rods 19, the latter being anchored at their lower ends to the base of the hydraulic cylinder, said rods being outside of the press chamber. The joint between the movable platen or ram and the fixed cooperating part is sealed with a labyrinth packing 20 of the character previously described but the packing is made somewhat deeper than the other so as to permit the lower platen or ram to move far enough to compress the charge. After the charge is deposited on the movable platen or ram of the elevator, it is raised by admitting water to the cylinder subject to the control of valve 21 and sufficient pressure is applied to firmly seat one part of the charge on the other or others. While in this position, the charge is permitted to cool sufficiently to permit the copper or other fusing metal to harden or if desired, to a greater degree, after which the platen is lowered and the charge removed. The platen or ram is then elevated preparatory to receiving another charge.

In a furnace of this character having as it does two ends which are capable of being opened, it is preferable to open only one end at a time so as to prevent a direct circulation of the controlled atmosphere throughout the furnace.

From the foregoing description it will be seen that the furnace is very simple in construction and may be considered to comprise a central heating chamber 4 communicating with end chambers, the open tubular lower ends of which are closed by the elevator platens. One of the end chambers designated at 22, while practically a part of the heating chamber, serves as a charging or loading chamber to take the charges pre-

sented by the elevator associated therewith, while the other end chamber 9 serves as a receiving chamber for the heated charges as well as a combined cooling and pressing chamber for the charges, the elevator associated therewith functioning along with the upper platen as a press during the cooling operation.

The delivery end chamber is separated from the heating chamber by a removable partition member which withholds the heat without preventing circulation of the gas. The partition member may be cooled in any suitable manner, for example, after the manner of the platens in chamber 9.

With this furnace arrangement, charges may be continuously withdrawn from the delivery end and new ones added at the receiving end without dilution or loss of gas to any appreciable extent because the end elevators are independent of each other and may be operated alternately, and because they operate automatically to close the openings through which the charges are taken and delivered, that is, the platens on which the charges are carried serve as closures for the necessary openings in the furnace.

The platens project into their respective tubular furnace openings sufficiently to bring their charge supporting surfaces substantially flush with the floor of the heating chamber so that the charges may be moved through the furnace from the receiving chamber to the heating chamber, and from the heating chamber to the delivery chamber entirely by means of the actuator 10 without being lifted. The platen surfaces are then comparatively widely separated from the packings 15 and 20 and are therefore well above the mouth of each furnace opening.

The elevator platens thus not only serve as closures for the openings in the furnace but when in place to close said openings, also provide a portion of the floor of the furnace which is thereby rendered continuous from one end of the furnace to the other.

What I claim as new and desire to secure by Letters Patent of the United States, is:

1. In a furnace, the combination of a casing having a chambered interior, one wall of which casing adjacent each end is provided with an opening, a movable platen associated with each of said openings to normally close the same, said platens being adapted to carry a charge to and from the casing, a receiving chamber located at one end of the casing, means connected with the casing for moving a charge therethrough from one platen to the other, means in said receiving chamber and associated with one of said platens for compressing a charge, and a heating chamber in the casing between said end openings.

2. In a furnace, the combination of a casing having a chambered interior, the bottom

wall of which casing adjacent each end is provided with an opening, a movable elevator platen associated with each of said openings to normally close the same, said platens being adapted to support a charge within the casing, means connected with the casing for moving a charge therethrough from one platen to the other, means associated with one of said platens for compressing a charge in a substantially vertical direction, and a heating chamber in the casing between said end openings.

3. In a furnace, the combination of a casing having a chambered interior, the bottom wall of which casing adjacent each end is provided with an opening, a movable elevator platen associated with each of said openings to normally close the same, said platens being adapted to support a charge within the casing, means connected with each platen for moving the same to carry a charge to and from the casing, means connected with the casing for moving a charge therethrough from one platen to the other, a heating chamber in the casing between said end openings, a cooling chamber in said casing, means associated with one of said platens for compressing a charge while in said cooling chamber and a removable heat resistant partition between the last-named platen and the heating chamber.

4. In a furnace, the combination of a casing, a heating chamber therein, said casing having openings in the bottom wall thereof adjacent opposite ends of the heating chamber, elevator means associated with each of said openings for opening and closing the same, said means including platens for carrying charges to and from the casing interior through said openings, means for moving charges from one platen to the other through the heating chamber, and means associated with one of said platens for compressing a charge while in the casing in a substantially vertical direction.

5. In a furnace the combination of a casing providing a heating chamber, said casing having an opening at each end in its bottom wall, conduit means for maintaining a supply of selected gas in said heating chamber, means for introducing a charge into the chamber through one of said openings, and elevator means movable upward through the other opening to compress the charge and downward to remove the charge through said opening.

6. In a furnace having a bottom wall and an opening therethrough at each end of said furnace, the combination of a heating chamber, conduit means for maintaining therein a supply of selected gas, means for introducing a charge into said chamber through one of said openings, said means comprising a movable platen operating through said opening, a receiving chamber located at the other end

of the heating chamber to receive the heated charge and means located within the receiving chamber including platen means extending through the other opening for compressing the charge and for removing the charge through said opening.

7. In a furnace having a bottom wall and an opening therethrough at each end of said furnace, the combination of a heating chamber, conduit means for maintaining therein a supply of selected gas, means for introducing a charge into said chamber through one of said openings comprising a movable platen operating through said opening, a receiving chamber located at the other end of the heating chamber to receive the heated charge, means located within the receiving chamber including platen means movable upward through the other opening to compress the charge and movable downward through said opening to remove the charge, and packing means for said platens.

8. In a furnace having a wall and an opening therethrough, the combination of a heating chamber, conduit means for maintaining therein a supply of selected gas, means for introducing into the chamber at one end a charge comprising separate pieces which are to be united by fusion and a fusing metal, said means comprising a movable platen which operates through the opening in the furnace, said platen being provided with a surface for supporting a charge and a packing for sealing the opening, said packing being in spaced relation to said surface in the direction of movement of the platen, a receiving chamber located at the other end of the heating chamber to receive the heated charge, means located within the receiving chamber for pressing the pieces of the charge into firm contact to insure proper fusion thereof, said means comprising a fixed platen, a movable platen, and means for moving the last-named platen in the direction of the fixed platen to compress the charge and in the opposite direction to withdraw it with the charge from the furnace.

9. In a furnace, the combination of a heating chamber, conduit means for maintaining therein a supply of selected gas, means for introducing into the chamber through an opening at one end a charge comprising separate pieces which are to be united by fusion and a fusing metal, said means comprising a movable platen which registers with the opening in the furnace, a receiving chamber located at the other end of the heating chamber to receive the heated charge, means located within the receiving chamber for pressing the pieces of the charge into firm contact to insure proper fusion thereof, said means comprising a fixed platen, a second movable platen, and means for moving the last-named platen in the direction of the fixed platen to compress the charge and in the opposite direc-

tion to withdraw it with the charge from the furnace, said receiving chamber being provided with an opening through which the last-named platen moves and said platens being each provided with a charge supporting surface and a packing for sealing the opening through which it moves, said packings being each in spaced relation to their respective charge supporting surfaces.

In witness whereof, I have hereunto set my hand this 6th day of July, 1927.
